CARL FLAKER, OF FLORISSANT, MISSOURI

INTERNAL COMBUSTION ENGINE

Application filed June 19, 1929. Serial No. 372,057.

This invention relates to internal engines and has for its principal objects to provide an efficient slide valve mechanism for controlling the supply of combustible mixture to and the exhaust of burned gases from the working cylinder of the engine. Another object is to provide for holding the valves to their seats regardless of wear, expansion or contraction of parts due to temperature changes. Other objects are simplicity and cheapness of construction, ease of assembly, fewness of parts and compactness of design.

The invention consists in the valve mechanism and in the construction, combination and arrangements of parts hereinafter described and claimed.

In the accompanying drawings, which form part of this specification and wherein like symbols refer to like parts wherever they occur,

Fig. 1 is a vertical central longitudinal section through a cylinder of an internal combustion engine provided with a valve mechanism embodying my invention; and

Fig. 2 is a horizontal cross-section on the line 2—2 in Fig. 1.

Referring to the accompanying drawings, my invention is shown in connection with an internal combustion engine comprising a cylinder 1 having a piston 1a reciprocating therein, and diametrically opposite intake and exhaust ports 2 and 3, respectively, in communication with the clearance space or combustion chamber 4 located between the upper end of said piston and the head 5 of said cylinder. The piston 1a is connected to the crank shaft (not shown) of the engine by means of the usual piston rod (not shown); and the intake and exhaust ports 2 and 3 may be connected in any suitable manner with the usual exhaust and intake manifolds (not shown) of the engine. As shown in the drawings, the head 5 of the cylinder is provided with an opening adapted to receive an igniting device or spark plug 6.

The inlet and exhaust ports 2 and 3 are opened and closed by means of valves 7 disposed within the combustion chamber 4 of the cylinder 1 and slidably longitudinally thereof across the inner ends of said ports.

Said valves preferably comprise diametrically opposed duplicate concavo-convex blocks or members whose convex surfaces are in contact with the bore of the cylinder and have a radius of curvature corresponding to the radius of curvature of said bore. The slide valves 7 are supported on the lower ends of valve stems 8 arranged for rotary and vertical sliding movement in bores provided therefor in diametrically opposed upstanding bosses 9 on the cylinder head 5. The lower end of each valve stem is provided with an offset or eccentric pin portion 10, which extends through an elongated vertical opening 11 provided therefor in the slide valve supported by said stem. The lower end of the eccentric portion 10 of the valve stem 8 is provided with a cross-head 12 that extends on opposite sides of the slot 11 in the slide block 7 and thus serves to hold said block on said stem. The cross-head of the valve stem is made smaller than the slot in the slide valve, whereby said valve may be mounted on and removed from the valve stem when the latter is rotated to bring the cross-head thereof into register with said slot. The valve stem is provided adjacent to the upper face of the slide valve with a collar portion 13 forming a shoulder or stop against which the upper face of said valve abuts. The stop collar 13 of the valve stem seats in a counter-bore 14 provided therefor in the head of the cylinder and is provided with a beveled surface 15 which, in the closed position of the valve, seats against a beveled seat 16 in the upper end of said counterbore and thus prevents leakage around the valve stem.

Sleeved on the upstanding boss 9 for each valve stem 8 is a coil spring 17 whose lower end 18 is anchored in a hole provided therefor in said head and whose upper end 19 is seated in a hole provided therefor in a collar 20 that is pinned or otherwise non-rotatably secured to the upper end of a valve stem. In assembling the parts, the spring 17 is twisted slightly in the direction in which it is wound, whereby said spring acts after the manner of a torsion or twist spring and thus tends to rotate the valve stem 8 in a direction which will force the eccentric

pin 10 thereof against the outer wall of the elongated slot 11 in the slide valve 7 and thus maintain the convex face thereof in contact with the bore of the cylinder.

5 The spring supported valve stems 8 are forced downwardly in alternation by means of rock levers 21 that are mounted for vertical swinging movement on diametrically opposite upstanding lugs 22 on the cylinder head 5. The inner arms of the rock levers 21 are provided with rollers 23 adapted to bear against the upper ends of the respective valve stems; and said levers are actuated by means of push rods 24 that engage their outer arms and, in turn, are actuated by the usual operating cams (not shown).

The hereinbefore described valve mechanism has many advantages. It is simple in construction, has few parts and is easily operated. It permits the valves to be readily mounted on and removed from the valve stems; and it maintains a gas tight joint between the valves and the cylinder regardless of wear or expansion or contraction of the parts due to temperature changes.

Obviously, the hereinbefore described valve mechanism admits of considerable modification without departing from the invention; and I do not wish to be limited to the precise forms and arrangements shown in the drawings.

What I claim is:

1. A valve assembly for an internal combustion engine comprising a valve having an opening therein, a rotatable valve stem having an eccentric portion freely movable in the opening in said valve, and a coil spring sleeved on said valve stem and tending to rotate the same to cause the eccentric portion thereof to bear against one wall of said opening to press said valve to its seat.

2. A valve assembly for an internal combustion engine comprising a slide valve provided with a threadless opening, a rotatable valve stem having a threadless eccentric portion extending into the threadless opening in said valve, and a spring cooperating with said valve stem to press the threadless eccentric portion thereof against one side of the threadless opening in said valve to hold the latter to its seat.

3. A valve assembly for an internal combustion engine comprising a slide valve having an opening extending therethrough, a rotary valve stem having an eccentric portion extending through and freely movable in the opening in said valve, and a spring tending to rotate said valve stem to press the eccentric portion thereof against one side of said opening in said valve to hold the same to its seat, said valve stem being provided with a cross-head adapted to bear against the undersurface of said valve and a shoulder adapted to abut against the upper surface

4. A valve assembly for an internal combustion engine comprising a valve member having an elongated slot extending therethrough, a valve stem having an eccentric portion extending through said elongated slot, and terminating in a cross-head extending on opposite sides of said elongated slot, said cross-head being made smaller than said elongated slot, whereby said cross-head is adapted to pass through said elongated slot when properly registered therewith, and a coil spring cooperating with said valve stem and tending to rotate the same to press the eccentric portion thereof against one wall of said elongated slot to thereby hold said valve to its seat and said cross-head in a position disposed crosswise of said elongated slot.

Signed at St. Louis, Missouri, this 15 day of June, 1929.
